G. MINCHIN.
TRUNK CATCH.

No. 244,645.

Patented July 19, 1881.

Attest:

Charles H. Pele
Chas. Herr.

Inventor:

George Minchin.
by O Drake, Atty.

UNITED STATES PATENT OFFICE.

GEORGE MINCHIN, OF NEWARK, NEW JERSEY.

TRUNK-CATCH.

SPECIFICATION forming part of Letters Patent No. 244,645, dated July 19, 1881.

Application filed March 25, 1881. (Model.)

To all whom it may concern:

Be it known that I, GEORGE MINCHIN, a resident of Newark, in the county of Essex and State of New Jersey, have invented certain new and useful Improvements in Trunk-Catches; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to that class of trunk-catches in which a tang projecting from a plate secured to the lid enters a socket in a box-like plate secured to the body of the trunk and engages with a catch or hook adjusted in said box-like plate for the purpose.

The object of the invention is to impart increased strength to and to facilitate the manipulation of the device.

In the accompanying drawings, in which similar letters of reference indicate corresponding parts in each of the several figures, Figure 1 is a front elevation of a trunk-catch embodying my improvement. Fig. 2 is a view of the same, taken from the back, showing the arrangement of the parts on the inside. Fig. 4 is a vertical transverse section of the same taken 30 through line *x*, and Figs. 3 and 5 are detail views.

The invention consists in the peculiar construction, arrangement, and operation of the various parts, as will be hereinafter more fully described and finally claimed.

In carrying out my invention I construct a plate, *A*, from sheet or cast metal, having the usual screw-holes, *a*, and a tang, *b*, provided with a recess, *c*, as indicated in Figs. 1, 2, and 40 3, which plate is intended to be secured to the lid or body of a trunk, as will be readily understood. I also construct a box-like plate, *B*, having the usual screw-holes, adapted to be secured to the body or lid of the trunk, and 45 provided with a socket or opening, *d*, for the reception of the tang *b*, above mentioned, as indicated in Figs. 1 and 2. Said plate *B* is also provided with two posts or lugs, *e* *e'*, projecting from the inside thereof, upon which is loosely 50 adjusted a hooked bar, *f*, the latter being provided with apertures for the purpose, the

hooked end being supported on one side by means of a spring, *g*, coiled around the post *e*, and adapted to automatically engage with the tang *b* when the trunk is closed, as will be understood by referring to Fig. 4.

A rod, *C*, is adjusted transversely in the plate *B*, one end of which is bent or otherwise formed at a right angle therewith, to constitute a thumb or finger piece, *h*, by means of which to manipulate the rod from the outside, Figs. 1 and 5, said rod having its bearings in perforations or recesses *i* at each side of the plate *B*, as indicated in Figs. 1 and 2. At or near the center of the rod is a recess, *j*, through which passes the hooked bar *f*, as indicated in Figs. 2 and 4, so that, as will be seen by reference more particularly to the latter figure, the hooked bar *f* lies between said rod and the spring.

The action of the hooked bar is somewhat 70 peculiar, and is as follows: When the lid is being closed and the tang (its end being beveled) comes in contact with the inclined face of the hooked bar, as will be understood by reference to Fig. 4, the latter will be forced outward against the yielding spring, while the opposite end of said bar will be forced inward, the action of the spring tending to keep it in intimate contact with the rod, as well as into engagement with the recessed tang. In opening the trunk the thumb-piece is seized and turned backward or downward, which forces the hooked bar out of engagement with the tang into the position indicated by the broken lines in Fig. 4, which position it will retain as 85 long as desired, if the rod is turned far enough; if not it will resume automatically its normal position when the trunk is open, as indicated in the same figure.

It will be evident that the rod need not be 90 recessed of necessity, as shown in Fig. 5, as if one side of it were flat its entire length between the bearings its action upon the hooked bar would be the same, though the rod might not be quite so stiff.

The double bearing of the hooked bar upon the posts *e* and *e'* imparts great strength to the device, and is, therefore, important.

In order to facilitate the adjustment of the rod *C* in the box-like plate *B* the latter is recessed on the inside, at *k*, so that the rod can be slipped into its bearings, the angle end first,

without difficulty, and be prevented from accidental displacement by the shoulders on the bar coming in contact with the sides of the plate, as will be readily understood.

5 It will be observed that the rod C operates, in connection with the hooked bar and tang, upon the same principle of an ordinary key in a lock, except that it is permanently adjusted in the catch.

10 Having thus described my invention, what I claim as new, and desire to secure by Letters Patent, is—

15 1. In a trunk - catch, the combination of a plate provided with a recessed tang, a box-like plate having a socket or opening to receive said tang, and two posts or lugs projecting from the inside thereof, a hooked bar adapted to be loosely adjusted upon said posts, as shown, and to engage with said tang in closing the
20 trunk, a spring adapted to hold the said bar

and tang into engagement, and means, as described, disconnected from said hooked bar and tang, for operating the device, substantially as and for the purposes set forth.

2. In a trunk-catch having a box-like plate 25 provided with two posts, a hooked bar adjusted thereon, and a spring arranged and operating as described and shown, in combination with a rod passing transversely through said box-like plate, having a flat and rounded surface, and a finger-piece, arranged and operating in conjunction with said hooked bar and spring, as and for the purposes set forth.

In testimony that I claim the foregoing I have hereunto set my hand this 21st day of 35 March, 1881.

GEORGE MINCHIN.
